UNITED STATES PATENT OFFICE.

EMIL T. SUTHERLAND, OF IRON RIVER, MICHIGAN.

ROAD-MAKING MACHINE.

1,144,444.

Specification of Letters Patent. Patented June 29, 1915.

Application filed April 7, 1913. Serial No. 759,525.

To all whom it may concern:

Be it known that I, EMIL T. SUTHERLAND, a subject of the Czar of Russia, residing at Iron River, in the county of Iron and State 5 of Michigan, have invented certain new and useful Improvements in Road-Making Machines, of which the following is a specification, reference being had to the accompanying drawings.

10 This invention relates to new and useful improvements in road making machines, and more particularly to a log road making machine wherein ice tracks are provided, and the primary object of the invention is to provide a device of this character which will in one operation form the tracks and road and supply water thereto for freezing.

Still another object of the invention resides in providing a device which levels the 20 road at the same time the tracks are provided and removes the snow and dirt to the sides of the tracks after forming the latter, and a still further object resides in providing a device which is simple and durable in 25 construction, inexpensive to manufacture, and one which will be very efficient and useful in operation.

With these and other objects in view, the 30 invention consists in the novel features of construction, combination and arrangement of parts as will be hereinafter referred to and more particularly pointed out in the specification and claims.

In the accompanying drawing forming a 35 part of this application, Figure 1 is a side elevation of the machine. Fig. 2 is a top plan view, with a portion of the tank removed. Fig. 3 is a perspective view of the plow with the track forming members carried thereon; and Fig. 4 is a similar view 40 of one of the knives or track forming members removed.

In describing my invention, I shall refer 45 to the drawing in which similar reference characters designate corresponding parts throughout the several views and in which—

1 designates a sleigh composed of two pairs of runners 2 and 3, of the usual or any desired size and shape, and suitably connected by means of the rods 4 and chains 5. Mounted on each pair of runners and extending transversely thereacross, is a bolster 50

6, a forward pair of runners having suitably connected thereto the pole 7. The double tree 8 is carried on said pole, whereby 55 suitable draft devices may be applied to the machine.

Suitably mounted forward of the rear 60 sleigh shoe 3, is the V-shaped plow or the like 9 which, when the machine is applied to use, extends across the road-way and has the free ends of the shares thereof projected beyond the sides of the runners. As shown in Figs. 1 and 2 of the drawing, the 65 flexible connections 5, which are in the form of chains, are secured at one of their ends to the forward ends of the rear runners 3 and to the faces of the plow, while the other ends of the chains are secured to the bolster on the front runners 2 and these connections 70 are crossed as clearly shown in Fig. 2, thus permitting the rear runners 3 to be properly guided with respect to the front runners 2, as the device is propelled. Adjustably secured on each of the shares of the plow 9, 75 is a knife or track former 10 which, as the device is propelled along the road-way, forms the desired track. These knives 10 are, of course, secured on the shares in the same longitudinal plane as the runners, the 80 space between the two knives being the universal tread of sleighs and other vehicles for road forming devices. In securing the knives to the plow, I have provided a pair of blocks 9'. These blocks are V-shaped 85 in cross-section and dispose the front faces of the knives in a plane angular to the plane of the shares of the plow. The knives are provided with a longitudinal slot 10'. Bolts and nuts 10^a are carried by the blocks 9' and 90 these in connection with the slot 10' form a locking and adjusting means for the knives. It can be easily seen that upon adjusting the knives various depths may be attained. As the device is propelled along the road-way, 95 all undesired turf, snow and the like is removed by the plow 9 and thrown toward the outer free ends of the arms thereof as is also the dirt and the like which is removed from the road-way in the formation 100 of the tracks by the knives or members 10.

Mounted for pivotal movement on the bolsters 6 is a tank 11, the rear end of which is provided with a pair of sprinkling nozzles

12. As the device is propelled and the tracks are formed in the road-way, water from the tank 11 is permitted to flow from the nozzles 12 into the tracks so formed and 5 when the water in said tracks freezes, it will be seen that ice tracks will be provided which are extremely desirable in the hauling of logs in frozen zones. If desired, the 10 sleigh used for forming the tracks with the tank carried thereon may also be used for hauling the logs by merely removing the plow and the tank therefrom.

It is of course to be understood that the machine heretofore described is intended 15 for the specific purpose of forming snow roads for logging operations. The machine is expressly designed not to entirely clear the roads of snow, but to take off the snow from the surface of the road to a predetermined 20 depth and to cast this snow laterally beyond the rear pair of runners so as to form a track through the snow wider than the usual width of logging sleds. It is also designed to cut ruts or tracks in the snow 25 left upon the surface of the road for the runners of the logging sleds and ice these ruts or tracks. Inasmuch as this machine carries a relatively heavy tank nearly filled with water, which tank will press down 30 very deeply upon the sled runners, it is necessary that the plow shall be free from rigid connection with either the front or the rear pairs of runners, as otherwise the plow would be forced down too deeply into 35 the snow and would take off too large a mass of snow so that the rut cutters would cut into the earth. It will be seen therefore that the plow is not connected to the rear pair of runners, but is disposed in front of 40 them, and that it is only flexibly connected with the front pair of runners. The plow is kept to its work, however, by the chains which pass over the upper portion of the plow and to the rear runners. The weight 45 of the plow, however, controls to a very large extent its depth of cut.

The plow is disposed immediately in front of the rear runners so that the rut or track cutters 10 shall be immediately in front of 50 and in alinement with the forward ends of the rear runners so that the rear runners shall track in the ruts formed by the cutters 10. It will be noted that these cutters are disposed at right angles to the line of draft, and therefore at an angle to the wings or shares of the plow. Thus these, cutters push the snow ahead of them gradually piling the snow in front of the cutters and this piled up snow gradually passes 55 under the cutters and is packed by the relatively heavily weighted rear runners so as to form a relatively solid mass of snow at the bottom of each track or rut. This tightly packed mass of snow at the bottom 60 of each rut is afterward wetted by the water 65

from the tank and freezes solidly, thereby providing a relatively deep track or rut along which the log sleds may run. This track or rut is not deep enough to interfere with the easy forward movement of the 70 log sleds, but is just deep enough to keep the log sleds in position so that the power of the draft animals may be used entirely for the purpose of drawing the sleds forward. It is to be noted that the chains 75 leading from the forward sled to the runners of the rear sled are crossed, and that the chains leading from the forward sled to the wings or shares of the plow are also crossed. This construction is necessary in 80 order that the rear sled may track properly in turning curves, and that the plow, while flexibly connected may at the same time be kept in such position that the cutters 10 will at all times be kept immediately in 85 front of the rear runners.

From the foregoing it will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to without departing 95 from the spirit or sacrificing any of the principles of the invention.

Having thus described this invention, what is claimed is:—

1. A machine for making logging roads 100 through snow, including forward and rearward sleds flexibly connected to each other, a V-shaped plow disposed forward of the rear sled flexibly connected to the forward sled and having free vertical movement independently of the rear sled, the shares of the plow extending laterally beyond the runners of the rear sled, and rut cutters mounted on the plow shares immediately in front of the rear runners. 110

2. A road machine including forward and rear sleds, each having a pair of runners, said sleds being flexibly connected with each other, a V-shaped plow disposed between the forward and rear sleds flexibly connected with the forward sled and having vertical movement independent of the rear sled, the shares of the plow extending laterally beyond the runners of the rear sled, and rut cutters disposed immediately in front of the rear runners and mounted on the shares of the plow, said cutters being disposed with their forward faces at right angles to the line of draft. 115 120

3. A road machine including forward and rear sleds, crossed connections flexibly connecting the sleds to each other, a V-shaped plow disposed between the forward and rear sled, crossed connections flexibly connecting the plow to the forward sled, the shares of 125 130

the plow extending laterally beyond the runners of the rear sled, and rut cutters mounted on the plow shares inward of the ends of the shares, immediately in front 5 of the rear runners, the faces of said cutters being disposed at right angles to the line of draft.

In testimony whereof I hereunto affix my signature in the presence of two witnesses.

EMIL T. SUTHERLAND.
